APPARATUS FOR STACKING WALLBOARD PANELS AND THE LIKE

Douglas C. Jeffrey, deceased, late of Akron, N. Y.,
by Alberta Jeffrey, executrix, Akron, N. Y., as-
signor to National Gypsum Company, Buffalo,
N. Y., a corporation of Delaware

Application June 25, 1947, Serial No. 756,905

13 Claims. (Cl. 214—6)

1

This invention relates to apparatus for stacking wallboard panels and the like, and more particularly to such apparatus adapted to stack bundles of wallboard in a multiplicity of contiguous columns.

The principal object is to provide apparatus which receives a continuously moving line of wallboard bundles and automatically stacks the bundles on a transportable supporting structure into a plurality of contiguous columns.

Another object is to substantially eliminate the manual labor which would otherwise be required to stack the bundles.

Another object of the invention is to provide such stacking apparatus which does not damage the wallboard in stacking the same.

Another object is to provide such apparatus which is of high capacity and in particular will receive and handle the line of bundles normally discharged from a conventional bundling machine.

Another object of the invention is to provide such apparatus which is transportable and can readily be removed to permit the substitution of similar apparatus designed to handle other sizes of wallboard bundles.

Another object is to provide such apparatus which is relatively simple in construction, considering the functions which it performs, and which will stand up under conditions of severe and constant use without getting out of order or requiring adjustment or repair.

Other objects and advantages of the invention will appear from the following description and drawings in which:

Fig. 1 is a side elevational view of apparatus embodying the present invention.

Fig. 2 is an end elevational view of the apparatus viewed from the left-hand end of Fig. 1.

Fig. 3 is a top plan view thereof.

Fig. 4 is a fragmentary vertical enlarged transverse sectional view taken generally on line 4—4, Fig. 3.

Fig. 5 is a fragmentary view similar to Fig. 4 and showing a different position of the parts.

Fig. 6 is an enlarged fragmentary horizontal sectional view taken generally on line 6—6, Fig. 1.

Fig. 7 is a fragmentary vertical longitudinal view taken generally on line 7—7, Fig. 3.

Fig. 8 is a fragmentary vertical transverse sectional view taken generally on line 8—8, Fig. 7.

Fig. 9 is an enlarged fragmentary vertical longitudinal sectional view taken on line 9—9, Fig. 3.

2

Fig. 10 is an enlarged fragmentary horizontal sectional view taken on the line 10—10, Fig. 1.

Fig. 11 is a fragmentary vertical sectional view taken on line 11—11, Fig. 10.

Fig. 12 is a fragmentary transverse sectional view taken generally on line 12—12, Fig. 3.

Fig. 13 is an enlarged fragmentary longitudinal sectional view taken on line 13—13, Fig. 3.

Fig. 14 is an enlarged fragmentary vertical transverse sectional view taken on line 14—14, Fig. 1.

Fig. 15 is a longitudinal vertical sectional view through an elevator forming part of the apparatus and which is adapted to be vertically moved above and below floor level.

Fig. 16 is a fragmentary view similar to Fig. 15 and showing the manner in which a skid or transportable supporting structure carrying a load of stacked bundles can be removed from the elevator, this view being on a slightly reduced scale as compared with Fig. 15.

Fig. 17 is an enlarged fragmentary vertical longitudinal sectional view taken on line 17—17, Fig. 3.

Fig. 18 is an enlarged fragmentary vertical transverse sectional view taken generally on line 18—18, Fig. 3.

Fig. 19 is a diagrammatic representation of the electrical wiring and components and the fluid pressure lines and components.

The apparatus embodying the present invention is shown as comprising a frame indicated generally at 20, arranged over a pit 21, this pit being preferably rectangular in horizontal cross-section and having operatively arranged therein a vertically movable platform 22. This platform can be withdrawn into the pit 21 and projected upwardly therefrom in any suitable manner, as

40 by a plunger 23 arranged in a hydraulic cylinder 24 in the bottom of the pit and having a line 25 through which fluid under pressure is introduced for moving the plunger 23 upwardly and having a line 26 through which the fluid in the cylinder

45 24 is exhausted to permit the plunger 23 to move downwardly.

The frame 20 is shown as made of skeleton construction from angle irons or the like and as having four vertical corner posts 28 which are

50 adapted to be removably supported on the floor and are shown as held against transverse displacement on the floor by means of pins 29 of any suitable construction. Main longitudinal bars 30 and main transverse bars 31 connect the upper ends of these posts, suitable reinforcing

plates being provided to insure rigidity of the structure. Main longitudinal bars 32 connect the posts 28 near their lower ends and a transverse bar 33 connects the lower ends of the posts 28 at the right-hand end of the frame as viewed in Fig. 1, the opposite or unloading end of the frame being unprovided with such lower transverse frame bar.

Conveyor means are provided to receive a line of bundles discharged in end-to-end relation from a conventional bundling machine such as the lath bundling apparatus disclosed in United States Patent No. 1,875,610, issued September 6, 1932. For this purpose a pair of horizontally spaced bars 34 project laterally from the main frame 20 of the apparatus at the right-hand end thereof as viewed in Fig. 3, and these bars are shown as being supported by means of braces 35. These bars 34 jointly carry a plurality of spaced rollers 36 which support the bundles B of wallboard so received in end-to-end relation from the bundling machine, the line of bundles being brought into alignment with a guide plate 38 by means of a pair of rubber rollers 39. The guide plate 38 is arranged at one side of the line of bundles moving over the rollers 36 and the rubber rollers 39 are mounted on the opposite side of this line of bundles and rotate about vertical axes.

On entering the main frame 20 of the stacking apparatus, the leading bundle B is accelerated in its forward movement to separate it from the succeeding bundles in the line and to project it into the preliminary zone of operation before the next succeeding bundle is brought into this zone. For this purpose a belt 40 passes over a drive roller 41, a roller 42 arranged in the line of rollers 36, and an idler roller 43, the drive roller 41 being so arranged as to provide a horizontal stretch 44 in the belt passing over certain of the rollers 36, this upper stretch of the belt moving in the direction of the arrow shown in Fig. 4. This belt is moved at a higher rate of speed than the line of bundles B supplied to the apparatus by means of an electric motor 45 which, through a reducer 46 and chain drive 48, drives a shaft 49 to which the drive roller 41 is fixed. Referring to the wiring diagram, Fig. 19, it will be seen that this motor 45 is under control of a manual switch 47.

In order to insure movement of the leading bundle with the upper stretch 44 of this higher speed feed belt 40, a hold-down roll 50 is provided. This hold-down roll is shown as being made of relatively soft rubber and arranged in position to engage the upper face of the bundles B of wallboard in any suitable manner as by means of supporting arms 51 which can be secured to the main frame 20 of the apparatus in any suitable manner.

A line of rollers 52, suitably mounted on the main frame 20, receives the bundle B of wallboard so accelerated by the belt 40, this line of rollers 52 being in line with the rollers 36 but being shown as being substantially shorter in axial length than the rollers 36. The endwise movement of the bundle B along the rollers 52 is limited by an end stop plate 53 which can be adjustably mounted on the main frame 20 of the apparatus in any suitable manner.

Means are provided for moving each bundle B so stopped by the stop plate 53 in a horizontal plane and transversely of its line of movement along the conveyor rollers 36 and 52 toward the unloading end of the apparatus. For this pur-

pose a push plate 54 is arranged above the line of rollers 52 and is mounted for reciprocatory movement in a horizontal plane transversely of the path of the line of bundles B entering the apparatus. In its normal position the inner operative face of this push plate is arranged in line with the inner operative face of the guide plate 38, this guide plate 38 extending a substantial distance into the main frame 20 of the apparatus as best shown in Fig. 3. To so support this push plate 54 for such reciprocatory movement, this plate is shown as provided on its undersides with slides 55 which are received in slotted rails 56, these rails being suitably carried by the main frame 20 of the apparatus below the line of rollers 52 and projecting outwardly from the end of the frame 20, as best shown in Figs. 1 and 3. The outwardly projecting ends of the rails 56 carry a rock shaft 58, this rock shaft being journaled to extend transversely of the rails 56 and having a crank 59 secured to each end thereof. The free end of each crank 59 is connected by a link 60 with the corresponding end of the push plate 54. The rock shaft 58 can be oscillated in any suitable manner to reciprocate the push plate 54, the rock shaft 58 being shown as provided for this purpose with a rock arm 61, the free end of which is connected to a piston rod 62 of a piston 63, this piston being shown as arranged in a pneumatic cylinder 64. The end of the cylinder 64 opposite that from which the piston rod 62 projects is shown as being pivotally secured to the main frame 20 of the apparatus as indicated at 65. The cylinder 64 is provided with lines 66 and 68 for alternately introducing and relieving fluid under pressure from opposite ends of the same to actuate the piston contained therein.

Each bundle B is moved by the push plate 54 toward the unloading end of the apparatus to be slidably received and supported on a pair of retractable rails 70 extending longitudinally of the apparatus adjacent opposite sides thereof. Each of these retractable rails 70 is shown as supported on the inner extremities of a pair of slides 71, each of these slides being slidably supported in a slideway 72 for movement transversely of the main frame 20 of the apparatus. One slideway 72 of each pair of the same is shown as being mounted on the corresponding corner post 28 and the other slideway of each pair is shown as being mounted on an intermediate vertical strut 73, each of these struts 73 being secured at its upper end to the corresponding upper longitudinal side beam 30 of the main frame and at its lower end to the corresponding lower longitudinal beam 32 thereof.

Means are provided for projecting the rails 70 into operative position to receive the bundles B from the push plate 54 and for retracting these rails to an inoperative position. For this purpose a horizontal longitudinal rock shaft 74 is journaled on each side of the main frame 30 of the apparatus and has a crank disk 75 fast to each end thereof. Each crank disk is provided with a crank pin 76 extending through a vertical slot 78 provided in a riser 79 fast to the corresponding slide 71. The rock shaft 74 can be oscillated in any suitable manner. For this purpose the pair of crank disks 75 at the center of the apparatus are each shown as provided with a crank pin 89, each of these crank pins being connected by a shipper rod 81 with one end of a bell crank lever 82. This bell crank lever is shown as pivoted at 83 its center, as indicated at 83, between a pair of

upper intermediate transverse frame bars 84 connecting the central parts of the longitudinal upper frame bars 30. The other end of the bell crank lever 82 is shown as connected by an adjustable link 85 with one end of a walking beam 86, this walking beam being pivoted at its center to the upper intermediate transverse frame bars 84 in any suitable manner, as indicated at 88. The walking beam 86 is shown as actuated by a fluid pressure mechanism comprising a piston rod 89 pivotally secured to one end of the walking beam 86 and connected to a piston 90 in a cylinder 91. The end of the cylinder 91 opposite that from which the piston rod 89 projects is shown as pivotally secured to the upper intermediate transverse frame bars 84 as indicated at 92. The cylinder 91 is provided with lines 93 and 94 for alternately introducing and relieving fluid under pressure from opposite ends of the same to actuate the piston contained therein.

The bundles B are guided in their movement along the retractable rails 70 and for this purpose a guide plate 95 is arranged above each retractable rail 70 and extends longitudinally thereof. Means are provided to move each guide plate 95 upwardly and outwardly to an inoperative position. For this purpose each guide plate 95 is fastened to the free ends of a pair of arms 96, the opposite ends of which can be pivotally secured to the main frame 20 of the apparatus in any suitable manner, as indicated at 98.

In order to so swing the guide plates 95 upwardly and outwardly to an inoperative position, a shaft 99 is shown as arranged longitudinally along each side of the apparatus above the arms 96 and journaled on the main frame 20 of the apparatus. Each of these shafts 99 carries a pair of disks 100, each of which has a crank pin 101 connected by a chain 102 with the free end of the corresponding arm 96, as best shown in Fig. 12. The shafts 99 are interconnected adjacent the feed end of the apparatus by an adjustable cross chain 103 so as to rotate in opposite directions. One of the shafts 99 adjacent the unloading end of the apparatus is provided with a hand wheel 104 and also a ratchet wheel 105 which cooperates with a releasable pawl 106 for holding the guide plates 95 in the elevated inoperative position shown by dotted lines in Fig. 12. The pawl 106 is shown as being operated by an eccentric hand lever 108.

It is essential that each bundle B be correctly aligned with the guide plates 95 before being pushed onto the retractable rails 70 by the push plate 54. This alignment is primarily effected by the stop plate 53 against which the accelerating belt 40 pushes the leading end of each bundle B. However, to insure proper registry of the bundles B so stopped by the stop plate 53 with the guide plate 95, it is desirable to prevent the bundle B from rebounding from the stop plate 53.

To prevent retrograde movement of the bundles B after engaging the stop plate 53, a compressible back stop 109 is mounted for vertical movement in a bracket 110 carried by the main frame 20 of the apparatus, as best shown in Fig. 5. This back stop is shown as arranged between the adjacent end rollers at the lines of rollers 36 and 52 and is formed to provide an inclined face 111 permitting forward movement of the bundles B thereover and an abrupt stop face 112 which prevents reverse movement of the bundle relative thereto. This backstop can be mounted for vertical movement in any suitable manner, as by

means of a pair of depending posts 113 slidably mounted for vertical movement in the bracket 110 and one of which can be provided with a helical tension spring 114 normally urging the back stop 109 into an elevated position in the path of the passing line of wallboard.

After a predetermined number of the bundles B have accumulated on the retractable rails 70, these rails are retracted so as to release the bundles and permit them to drop as a unitary group. These bundles are received by a transportable supporting structure in the form of a skid 115 which is removably arranged on the elevator platform 22. In order to insure proper positioning of this skid 115 upon the platform 22, an abutment plate 116 is preferably provided on this platform. An empty skid 115 can be placed upon the platform 22 and the loaded skid removed from this platform in any suitable manner as by means of the truck hoist 118 shown in broken lines in Fig. 16. In placing the skid on and removing it from the platform 22, the platform is brought to floor level as shown in this figure.

The various mechanisms of the stacking apparatus as above described are synchronized in their operation so that a continuous line of wallboard bundles is received from the bundling machine and stacked upon the skid 115. Referring again to the line of wallboard bundles B moved by the accelerating belt 40 against the stop plate 53, it will be noted, upon reference to Figs. 3 and 6, that when the leading end of each bundle B strikes the stop plate 53 it also strikes and moves a trip lever 120 which extends through an opening 121 in the stop plate 53 and is normally maintained in the projected position shown in Fig. 3 by a spring 122. This trip lever 120, when actuated by the advance end of each bundle B throws the arm 123 of a normally open magnetic holding switch 124, this switch being of the type that remains closed as long as current is flowing through it. Referring to the diagram, Fig. 19, this normally open magnetic holding switch is arranged across the sides 125 and 126 of the main power line and in series with a normally closed reversing switch 128 and a solenoid valve 129. This solenoid valve is so constructed that when energized it permits the flow of fluid from a line 130 to the line 68 leading to one end of the cylinder 64 and opens the line 66 from the opposite end of this cylinder to an exhaust or return line 131. When de-energized, this solenoid valve 129 connects the pressure line 130 with the cylinder line 66 and opens the cylinder line 68 to the return or exhaust line 131.

Since the reversing switch 128 is normally closed it will be seen that when the advance end of the bundle B striking the lever 120 closes the normally open magnetic holding switch 124, the solenoid valve 129 is energized to admit fluid under pressure through the line 68 to the closed end of the cylinder 64 and thereby drive its piston 63 and piston rod 62 outwardly, the fluid on the opposite side of the piston being relieved through a line 66 to permit this movement. This movement of the piston rod 62, as best shown in Fig. 7, advances the push plate 54, this movement being effected through the linkage comprising the rock arm 61, rock shaft 58, crank arm 59 and link 60. This advancing movement of the push plate 54 pushes the stopped bundle B horizontally onto the adjacent ends of the retractable rails 70. The advancing movement of the push plate 54 continues until the normally closed stop

switch 128 is opened. For opening this stop switch at the end of the forward stroke of the push plate 54, the rock shaft is provided with an arm 132 which, at the extreme end of the forward stroke of the push plate 54, engages and moves the arm 133 of this normally closed stop switch, as best shown in Fig. 17. When this normally closed stop switch 128 is so opened by the arm 132 it de-energizes the normally open magnetic holding switch 124, so as to permit this switch to resume its open condition, and also de-energizes the solenoid valve 129. Upon the de-energization of the solenoid valve the pressure supply line 130 is connected with the line 66 of the cylinder 64 and the line 68 of this cylinder is connected to the exhaust or return line 131, and hence it will be seen that the piston 63 and its piston rod 62 will be moved in reverse direction to retract the push plate 54 to its normal retracted position illustrated in Fig. 3 in which its operative face is in line with the operative face of the guide plate 38 so that the next succeeding bundle can be advanced along the rollers 52 by the accelerating belt 48 into a position opposite the operative side of the push plate 54.

As each wallboard bundle B is pushed by the push plate 54 onto the retractable rails 70, a line of these bundles B accumulates on these rails inside by side relation, this line being advanced as each new bundle is pushed onto these rails by the push plate 54. When a predetermined number of these bundles B, six being shown, so accumulates on the retractable rails 70, the leading edge of the foremost bundle reaches the ends of these retractable rails 70 at the unloading end of the apparatus. Upon reference to Figs. 8, 9 and 10, it will be noted that when the last or sixth bundle B of the line is being pushed onto the retractable rails 70 the leading edge of the first or foremost bundle B of this line strikes and moves a trip lever 135 which is fast to a small cross shaft 136 suitably journaled on one of the retractable rails 70 at the unloading end of the apparatus. This trip lever 135 normally projects up through a slot 138 in this retractable rail 70 and is yieldingly held in this upwardly projected position by a counterweight arm 139 fast to the shaft 136. The counterweight arm engages the arm 140 of a normally open magnetic holding switch 141, this switch being of the type that remains closed as long as current is flowing through it. The trip lever 135, when depressed by the advance edge of the foremost bundle B of the line of bundles advancing along the retractable rails 70, moves the counterweight arm 139 to throw the arm 140 of the normally open magnetic holding switch 141 to close this switch. The normally open magnetic holding switch is mounted on the same retractable rail 70 which carries the trip lever 135.

Referring to the diagram, Fig. 19, this normally open magnetic holding switch 141 is arranged across the sides 125 and 126 of the main power line and in series with a normally closed reversing switch 142 and a solenoid valve 143. This solenoid valve is so constructed that when energized it permits the flow of fluid from the line 130 to the line 94 leading to one end of the cylinder 91 and opens the line 93 from the opposite end of this cylinder to an exhaust or return line 144. Since at this time the reversing switch 142 is closed, it will be seen that when the advance edge of the foremost bundle B of the line of these bundles advancing along the retractable rails 70 strikes the trip lever 135 and closes the nor-

mally open magnetic holding switch 141, the solenoid valve 143 is energized to admit fluid under pressure through the line 94 to the corresponding end of the cylinder 91 and thereby retract its piston 90 and piston rod 89, the fluid on the opposite side of the piston being relieved through line 93 to permit this movement. This movement of the piston rod 89, as best shown in Figs. 2 and 12, retracts the retractable rails 70, this movement being effected through the linkage comprising the walking beam 86, adjustable links 85, bell crank levers 82, shipper rods 81, disks 75, crank pins 76, and slides 74, which carry these retractable rails 70. When the retractable rails 70 are so retracted, the full line of bundles B contained on these retractable rails drops onto the skid 115 as a unitary group or layer, these bundles building up layer by layer on this skid until the same is fully loaded.

After a full line or layer of the bundles B has been so dropped on the skid 115 by this retraction of the retractable rails 70, the rails are immediately projected into their operative position to receive the next bundle B from the push plate 54. For this purpose one of the disks 75, as best shown in Figs. 7 and 8, has a reversing lug 145 secured thereto. As the retractable rails 70 approach their fully retracted position (Fig. 12), this reversing lug 145 strikes the arm 146 of the normally closed reversing switch 142 and opens this switch. When this normally closed reversing switch 142 is so opened by the reversing lug 145, it opens the circuit through the normally open magnetic holding switch 141 and also de-energizes the solenoid valve 143. Upon de-energization of the solenoid valve 143, the pressure line 130 is connected with the line 93 of the cylinder 91 and the line 94 of this cylinder is connected to the exhaust or return line 144, and hence it will be seen that the piston 90 and its piston rod 89 will be extended to advance the retractable rails 70 to their normal inwardly projected position illustrated in Fig. 2, thereby to return these retractable rails to their operative position to receive successive lines of bundles advanced thereon by the push plate 54.

To facilitate removing loaded skids and placing unloaded skids on the platform 22, it is desirable to hold the retractable rails 70 in their retracted inoperative position shown in Fig. 12. To this end a manual switch 147 is shunted across the normally open magnetic holding switch 141 and reversing switch 142, as best shown in Fig. 19. This manual switch 147 is of any suitable type to remain either open or closed until manually operated and is illustrated in Figs. 1 and 19 as being of the double push button type. This switch 147 is, of course, normally open and is only closed to replace or remove the skid from the platform 60 22.

As each layer of bundles B is so dropped upon the skid 115 supported by the elevator platform 22, the elevator platform is lowered a distance equal to the thickness of this layer so that each layer is dropped from the retractable rails 70 an equal distance. For this purpose, as best shown in Figs. 1 and 13, a bell crank lever 150 is pivoted on the main frame 20 of the apparatus in any suitable manner so that one of its arms projects generally horizontally into the path of the layer of bundles B being dropped from the retractable rails 70. The bell crank lever 150 is shown as being arranged to engage one exposed end of the last or sixth bundle of each line or 65 70 75 layer of bundles released by the retractable rails

70. The other arm of this bell crank lever engages and operates the arm 151 of a normally open switch 152.

Referring to the diagram, Fig. 19, this normally open switch is arranged across the sides 125 and 126 of the main power line and in series with a normally closed solenoid valve 153. This solenoid valve is in the return line 26 from the plunger cylinder 24 supporting the plunger 23 of the elevator, and it will therefore be seen that when the switch 152 is closed the solenoid valve 153 is opened so as to permit the plunger 23 and platform 22 to lower. Accordingly, when a layer of bundles B is released by the retractable rails 70, the last or sixth bundle of this layer strikes the bell crank lever 150 thereby to close the switch 152 and energize the normally closed solenoid valve 153. Energization of the normally closed solenoid valve 153 opens this valve and permits fluid to escape from the plunger cylinder 24 and permits the elevator platform 22 to lower. The bell crank lever 150 is so disposed that the falling layer of bundles B engages the next proceeding layer of bundles before the side of the last or sixth bundle disengages the operating arm of the bell crank lever 150. Accordingly, the lowering of the platform 22 is gradual and continuous, this lowering continuing until the arm of the bell crank lever 150 is freed by the last or sixth bundle B, thereby permitting the bell crank lever 150 to return to its normally projecting position and also the switch arm 151 to return to its normally open position as shown in Fig. 1.

Any suitable means can be provided for elevating the platform 22, such means being preferably under manual control and being shown as comprising a manual switch 155 arranged across the sides 125 and 126 of the main power line, as best shown in Fig. 19, and in series with a normally closed solenoid valve 156. This solenoid valve is arranged in the line 25 supplying operating fluid under pressure to the plunger cylinder 24 and it will therefore be seen that to raise the platform 22 the operator closes the manual switch 155 thereby to energize the normally closed solenoid valve 156 and admit fluid under pressure to the plunger cylinder 24. The operator keeps the manual switch 155 closed, thus raising the plunger 23 and platform 22 until the desired elevation of this platform is obtained. During this operation the solenoid valve 153 is in its normally closed position and accordingly fluid cannot escape through the line 26 while fluid is so being supplied by the supply line 25. It will be noted that raising the platform 22 with a fully loaded skid thereon will not close the normally open switch 152. Thus, even with a fully loaded skid 115 on the platform 22, as the platform 22 is raised the last or sixth vertical stack of bundles on this skid merely swings the bell crank lever 150 away from the switch arm 151 of the normally open switch 152 and hence during this rising movement of the platform 22 the switch 152 is not actuated.

Operation

While it is believed that the operation of the apparatus is clear from the above description, the operation is briefly summarized as follows:

Assuming the platform 22 to be empty and at 70 floor level (Fig. 16), the operator first places the empty skid 115 upon this platform, using the hoist truck 118 for this purpose, in such a position that the inner end of the skid is against the vertical plate 116 (Fig. 15) on this platform so 75

as to properly align the skid for receiving the successive layers of bundles B dropped thereon. The operator then removes the hoist truck 118 and closes the switch 155 (Fig. 19), thereby energizing the normally closed solenoid valve 156. The opening of this valve permits fluid under pressure to flow through the supply line 25 to the plunger cylinder 24, this fluid under pressure thereby raising the plunger 23 and platform 22. 10 The operator holds the switch closed until the platform 22 is elevated a substantial distance above ground level and immediately below the bell crank lever 150, as shown in Figs. 1, 2 and 13, this establishing the distance which the layers of bundles are dropped onto the skid 115.

The operator then starts the bundling machine (not shown), and also closes the switch 47 (Fig. 19), for the motor 45. The motor 45 (Fig. 3), through the reducer 46, chain drive 48 and shaft 49, drives the drive roller 41 (Fig. 4) so as to drive the upper stretch 44 of the accelerating belt 40 in the direction of the arrow shown in Fig. 4. Accordingly, the leading bundle B in the line of bundles fed endwise by the bundling machine (not shown) onto the rollers 36 is engaged by the upper stretch 44 of the accelerating belt 40, the leading bundle B being accelerated in its movement to separate it from succeeding bundles and moved endwise onto the rollers 52 and

25 against the end plate 53. It will be noted that the backstop 109 is depressed by the leading bundle B passing thereover and released approximately when the advance end of the leading bundle engages the stop plate 53, this release of the backstop 109 permitting it to rise and dispose its stop face 112 in abutting relation with the trailing end of the leading bundle and thus preventing retrograde movement of the leading bundle. 30 The line of bundles B so advancing endwise on the rollers 36 are held in proper alignment by the guide plate 38 (Fig. 3) against which the bundles are urged by the rubber rollers 39. The bundles advancing endwise against the stop plates 53 are held in proper alignment on the rollers 52 by the push plate 54 which at this time has its operative face in alignment with the operative face of the guide plate 38.

The advance end of each bundle B striking the stop plate 53 also strikes the trip lever 120 which 35 is normally maintained in the projected position shown in Fig. 3. This trip lever 120, when so actuated by the advance end of each bundle B throws the arm 123 (Fig. 6) of the normally open magnetic holding switch 124 (Fig. 19), thereby 40 to close this normally open magnetic holding switch 124, this normally open magnetic holding switch remaining closed until its circuit is broken at another point. The closing of the normally open magnetic holding switch 124 permits 45 current to flow through the solenoid valve 129, the energization of which permits fluid under pressure to flow from the supply line 130 into the line 68 to the cylinder 64 and also permits fluid to escape from the opposite end of the cylinder 64 through the line 66 to the exhaust line 131. Accordingly, the piston 63 in the cylinder 64 is driven to the left as viewed in Fig. 19 so as to project its piston rod 62.

This outward movement of the piston rod 62 (Figs. 7 and 4) through the rock arm 61, rock shaft 58, crank 59 and link 60, moves the push plate 54 to the left as viewed in Fig. 7, this push plate being advanced along the horizontal rails 56 which guide the same to move in a horizontal plane. This movement of the push plate

strips the foremost bundle B from the rollers 52 and pushes the same onto the adjacent ends of the retractable rails 70.

This movement of the rock shaft 58 in so advancing the push plate 54 moves the arm 132 counterclockwise (Fig. 17) so as to engage and move the arm 133 of the normally closed reversing switch 128 and opening this switch (Fig. 19) de-energizes the magnetic holding switch 124, so as to permit this magnetic holding switch 124 to resume its normally open position, and also de-energizes the solenoid valve 129. De-energization of this solenoid valve 129 reverses the relation of its inlet and outlet lines so that fluid under pressure is now admitted to the line 66 from the supply line 130 and the line 68 is connected to the exhaust or return line 131. Accordingly, the piston 63 and its piston rod 62 are moved to the right as viewed in Fig. 19 so as to retract the piston rod 62. Retraction of the piston rod 62 (Figs. 7 and 4) effects a reversal or retracting movement of the push plate 54 through the linkage comprising the rock arm 61, rock shaft 58, crank 59 and link 60. This reverse movement of the push plate 54 continues until the piston 63 (Fig. 19) reaches the end of the cylinder 64, in which position the operative face of the push plate 54 is in alignment with the operative face of the guide plate 38 (Fig. 3).

This reciprocation of the push plate 54 by the piston is rapid and is synchronized with the speed of the accelerating belt 40 so that the cycle of operation of the push plate 54 occurs before the next succeeding bundle is accelerated by the accelerating belt 40 into a position to be acted upon by the push plate 54. The lateral displacement by the push plate 54 of the succeeding bundles continues until a given number of bundles are arranged abreast of each other on the retractable rails 70. In the present showing, the retractable rails 70 are designed to accommodate six bundles. As the sixth bundle is pushed onto the retractable rails 70 by the push plate 54, the leading end of the first of the line of bundles on the retractable rails engages and depresses the trip lever 135 (Figs. 3 and 9). This movement of the trip lever 135 through its counterweight arm 139 (Fig. 11) actuates the switch arm 140 to close the normally open magnetic holding switch 141, thereby to close this normally open magnetic holding switch 141 which remains closed until its circuit is broken at another point. The closing of the normally open magnetic holding switch 141 (Fig. 19) permits current to flow through the solenoid valve 143, the energization of which permits fluid under pressure to flow from the supply line 130 into the line 94 to the cylinder 91, and also permits fluid to escape from the closed end of the cylinder 91 through the line 93 to the exhaust line 144. Accordingly, the piston 90 is driven toward the closed end of the cylinder to retract its piston rod 89.

This retracting movement of the piston rod 89 through the walking beam 86 (Figs. 2 and 12), adjustable links 85, bell crank levers 82, and shipper rods 81, rotates the disks 75 on the rock shaft 74 and moves the crank pins 76 outwardly and upwardly. This movement of these crank pins 76 moves the slides 71 in the sideways 72 outwardly so as to withdraw the retractable rails 70 from their supporting position under the marginal portions of the full line of bundles B supported by these rails. This permits the full line of bundles B supported by these rails to drop or

fall as a unitary group upon the skid 115 arranged therebelow and forming the first layer thereon.

After a full line or layer of the bundles B has been so dropped on the skid 115 by this retraction of the retractable rails 70, the rails are immediately projected into their operative position to receive the next bundle B from the push plate 54. For this purpose, during the final retraction movement of the retractable rails 70, the reversing lug 145 (Fig. 8) on one of the crank disks 75 strikes the arm 146 of the normally closed reversing switch 142 (Fig. 19), and opens the switch. This opening of the normally closed reversing switch 142 opens the circuit through the closed magnetic holding switch 141, so as to permit this magnetic holding switch to resume its normal open condition and also de-energizes the solenoid valve 143. Upon de-energization of the solenoid valve 143 the pressure line 130 is connected with the line 93 of the cylinder 91 and the line 94 of the cylinder is connected to the exhaust or return line 144 and hence it will be seen that the piston 90 is moved to extend its piston rod 89 from the cylinder 91. This extending movement of the piston rod 89 (Figs. 2 and 12), through the linkage comprising the walking beam 86, adjustable links 85, bell crank levers 82, shipper rods 81, disks 75 and rock shaft 74 causes the crank pins to swing downwardly and inwardly. This moves the slides 71 carrying the retractable rails 70 inwardly so as to return these retractable rails 70 to their normally projected position illustrated in Fig. 2, thereby to return these retractable rails to their operative position to receive successive bundles advanced thereon by the push plate 54.

As each layer of bundles B is so deposited upon the skid 115, the elevator platform 22 is lowered a distance equal to the thickness of this layer. This is accomplished by the exposed longitudinal end of the last or sixth bundle of each layer engaging and holding the bell crank lever 150 (Figs. 1, 3 and 13), this bell crank lever being arranged immediately below the retractable rails 70 so that each layer of bundles B comes to rest on the skid 115 before the side of the last or sixth bundle disengages the operating arm of this bell crank lever. This bell crank lever is thereby moved and held so as to move the switch arm 151 and hold the normally open switch 152 in its closed position. The closing of the switch 152 (Fig. 19) permits current to flow through and energizes the normally closed solenoid valve 153, thereby opening the solenoid valve and permitting fluid to escape from the plungers cylinder 24 through the line 26 and permitting the elevator platform 22 to lower. The lowering of the platform 22 continues until the last or sixth bundle of the dropped layer 60 of bundles disengages the bell crank lever 150, this permitting the bell crank lever to resume its normal position projecting in the path of the next succeeding layer of bundles to be dropped. When the bell crank lever so returns to its normal position, the switch 152 opens to de-energize the normally closed solenoid valve 153 (Fig. 19), thereby closing the solenoid valve and preventing further escape of the fluid from the plunger cylinder 24 through the line 26 and retaining the platform 22 at an elevation lower by a distance corresponding to the thickness of the layer of bundles deposited on the skid. This depositing of successive layers of bundles B upon the skid 115 and the step-by-step lowering of the platform 22 continues until a full load of bundles has been de-

posed on the skid. It will be noted that these bundles are deposited in six contiguous columns or stacks (Fig. 16).

When a full load of bundles has been deposited upon the skid 115, the operator stops the bundler (not shown) thereby to cut off the line of bundles being fed to the apparatus and discontinuing the automatic operations above described. The operator then throws the switch 147 to its closed position, this closing a circuit through the solenoid valve 143 (Fig. 19). The closing of this solenoid valve 143 permits fluid to flow from the supply line 130 through line 94 to one end of the cylinder 91 and permits fluid to escape from the opposite closed end of the cylinder 91 through the line 93 to the exhaust or return line 144. This retracts the piston rod 89 and, through the linkage comprising the walking beam 86 (Figs. 2 and 12), adjustable links 85, bell crank levers 82, shipper rods 81, disks 75 and rock shafts 74, moves the crank pins 76 outwardly and upwardly. This moves the slides 71 outwardly thereby to move the retractable rails 70 carried thereby to the outwardly retracted inoperative position shown in Fig. 12.

The operator then turns the hand wheel 104 in a clockwise direction as viewed in Fig. 2, thus turning the two shafts 99 which are cross-connected by the chains 103. This rotation of these shafts 99 (Fig. 12) winds up the chains 102 so as to lift the guide plates 95 carried by the arms 96, these arms 96 swinging about their pivotal connections 98 with the main frame of the apparatus. These guide plates 95 and their supporting arms are moved to the approximate position shown by dot-dash lines in Fig. 12 and are retained in this position by the pawl 106 engaging the ratchet wheel 105 on one of the shafts 99 (Fig. 18).

In the fully loaded position of the skid 115 the platform 22 has been lowered a substantial distance below floor level and hence it is necessary for the operator to raise this platform to floor level in order to remove the skid. To so raise the platform the operator closes the manual switch 155 so as to energize the normally closed solenoid valve 156 (Fig. 19). Energization of this solenoid valve permits fluid to flow into the line 25 and bottom of the plunger cylinder 24 thereby to elevate the plunger 23 and platform 22 carried thereby. It will be noted that the solenoid valve 153 is closed at this time so that fluid cannot escape from the plunger cylinder 24 while fluid is being admitted through line 25. When the platform 22 reaches floor level the operator opens the switch 155 so as to de-energize the solenoid valve 156 and cut off the flow of fluid to the plunger cylinder 24.

The operator then places the hoist truck 118 under the loaded skid 115, lifts this skid and removes it from the platform 22. The operator then replaces an empty skid 115 upon the platform 22, placing this skid against the plate 116 as previously described.

The operator then closes the switch 155 (Fig. 19) so as to energize the normally closed solenoid valve 156. This permits fluid to flow from the supply line through the line 25 to the bottom of the plunger cylinder 24 and thereby elevate the plunger 23 and elevator platform 22 carried thereby. This energization of the solenoid valve 156 is continued until the platform is raised to approximately the level shown in Figs. 1 and 2, this position being such that the upper surface of the skid 115 is immediately below the bell crank

lever 150 (Fig. 13) and hence in position to be properly actuated by the first layer of bundles B falling upon the skid.

The operator then swings the hand lever 108 from the full to the dotted line position shown in Fig. 18, this camming the pawl 106 free from the ratchet wheel 105 and permitting the guide plates 95 to be lowered from the broken line position to the full line position shown in Fig. 12. After the guide plates 95 have so been restored to their full line operative position shown in Fig. 12, the operator throws the lever 108 to the full line position shown in Fig. 18, thereby to restore the pawl 106 in engagement with the ratchet wheel 105.

The operator then throws the switch 147 to its open position (Fig. 19) thereby de-energizing the solenoid valve 143. In this de-energized position of the solenoid valve 143, fluid from the supply line 130 is permitted to flow through the line 93 into the closed end of the cylinder 91, this solenoid valve also permitting fluid to be relieved from the opposite end of this cylinder through the line 94 and exhaust or return line 144. Introduction of fluid to the closed end of the cylinder 91 extends the piston rod 89 and returns the retractable rails 70 to their inwardly projected operative position shown in Fig. 2 in the manner previously described.

The apparatus has now been restored to the condition originally assumed and the cycle of operation is repeated.

It will be noted that the apparatus can be moved by first lifting the pins 29 (Figs. 1 and 2) and placing the apparatus on a hoist truck or the like to transport the apparatus to another location. This is an important feature of the invention since in the manufacture of wallboard different sizes of wallboard are run at different times and by having the entire apparatus portable another similar apparatus can readily be installed in its place to handle a different size wallboard.

It is obvious that the apparatus embodying the present invention can be used to stack individual wallboard panels as well as bundles of such panels as heretofore illustrated and described. Accordingly, the expression "wallboard panels and the like" as used in the accompanying claims is meant to include both individual wallboard panels as well as bundles thereof, and all other types of panels which are relatively large and heavy and difficult to handle manually.

From the foregoing it will be seen that the present invention provides an apparatus for automatically stacking wallboard or the like and which accomplishes the many objects heretofore set forth. It is intended, of course, that this invention should not be limited to the specific embodiments disclosed herein, since modifications may be made, and it is contemplated, therefore, by the appended claims to cover any such modifications as fall within the true spirit and scope of this invention.

I claim:

1. Apparatus for stacking wallboard panels and the like in a plurality of contiguous columns, comprising a conveyor adapted to convey a succession of said panels, support means arranged adjacent said conveyor to movably receive from said conveyor and support in a horizontal plane a plurality of said panels in side by side relation and movable to release any panels supported thereby, a second conveyor successively transferring individual panels from said first conveyor to said support means whereby successive panels so transferred to said support means move pre-

ceding panels along said support means in a horizontal plane, and means actuated in response to the accumulation of a predetermined number of said panels on said support means and moving said support means to release said predetermined number of panels and permit them to fall by gravity as a unitary group.

2. Apparatus for stacking wallboard panels and the like in a plurality of contiguous columns, comprising a conveyor adapted to convey a succession of said panels in a horizontal plane, a horizontal support means arranged adjacent said conveyor to movably receive from said conveyor and support in a horizontal plane coplanar with said first mentioned horizontal plane a plurality of said panels in side by side relation and movable to release any panels supported thereby, a second conveyor movable in a horizontal plane and successively transferring individual panels from said first conveyor to said support means whereby successive panels so transferred to said support means move preceding panels along said support means and remain in said coplanar horizontal plane while being transferred by said second conveyor, and means moving said support means to release the panels supported thereby when a predetermined number of said panels have accumulated thereon to permit said predetermined number of said panels to fall by gravity as a unitary group.

3. Apparatus for stacking wallboard panels and the like in a plurality of contiguous columns, comprising a conveyor adapted to convey a succession of said panels in a horizontal plane, a horizontal support means arranged adjacent said conveyor to movably receive from said conveyor and support in a horizontal plane coplanar with said first mentioned horizontal plane a plurality of said panels in side by side relation and movable to release any panels supported thereby, a second conveyor intermittently movable in a horizontal plane and in a direction transverse of the direction of movement of said panels on said first conveyor to successively transfer individual panels from said first conveyor to said support means whereby successive panels so transferred to said support means move preceding panels along said support means and remain in said coplanar horizontal plane while being transferred by said second conveyor, and means moving said support means to release the panels supported thereby when a predetermined number of said panels have accumulated thereon to permit said predetermined number of said panels to fall by gravity as a unitary layer.

4. Apparatus for stacking wallboard panels and the like in a plurality of columns, comprising a conveyor adapted to convey a succession of said panels, a pair of spaced horizontal retractable rails arranged adjacent said conveyor and adapted to receive a plurality of said panels from said conveyor and to engage said panels along their marginal portions, a second conveyor successively transferring said panels from said first conveyor to said rails, and means for retracting said rails to release the panels supported thereby when a predetermined number of said panels have accumulated thereon to permit said predetermined number of said panels to fall by gravity as a unitary group.

5. Apparatus for stacking wallboard panels and the like in a plurality of columns, comprising a conveyor adapted to convey a succession of said panels, a pair of horizontally spaced horizontal retractable rails arranged adjacent said conveyor

and adapted to slidably receive a plurality of said panels from said conveyor and to engage the underside of said panels along their marginal portions, a guide plate associated with each of said rails to maintain the alignment of said panels in their sliding movement along said rails, a second conveyor successively transferring said panels from said first conveyor to said rails, and means actuated in response to the accumulation of a predetermined number of said panels on said rails for retracting and returning said rails to release said predetermined number of said panels and to permit them to fall by gravity as a unitary group.

6. Apparatus for stacking wallboard panels and the like in a plurality of columns, comprising a horizontal conveyor adapted to convey a succession of said panels, a horizontal support arranged adjacent said conveyor and adapted to receive successively a plurality of said panels from said conveyor, a pusher independent of said support and arranged adjacent one side of said conveyor and reciprocable horizontally across said conveyor toward and from said support, power actuated means synchronized with the movement of said panels along said conveyor and arranged to reciprocate said pusher to successively transfer said panels from said conveyor to said support, and means actuated in response to the accumulation of a predetermined number of said panels on said support to move said support to release said predetermined number of panels.

7. Apparatus for stacking wallboard panels and the like in a plurality of columns, comprising a horizontal conveyor adapted to convey a succession of said panels, a horizontal support arranged adjacent said conveyor and adapted to receive successively a plurality of said panels from said conveyor, a pusher arranged adjacent one side of said conveyor and reciprocable horizontally across said conveyor toward and from said support, means for separating the leading one of said succession of panels from succeeding panels therein, means stopping the forward movement of said leading panel on said conveyor opposite the operative side of said pusher, power operated means actuated in response to the stopping of said leading panel and arranged to reciprocate said pusher to transfer said leading panel from said conveyor to said support, and means actuated in response to the accumulation of a predetermined number of said panels on said support to move said support to release said predetermined number of panels.

8. Apparatus for stacking wallboard panels and the like in a plurality of columns, comprising a horizontal conveyor adapted to convey a succession of said panels, a horizontal support arranged adjacent said conveyor and adapted to receive successively a plurality of said panels from said conveyor, a pusher arranged adjacent one side of said conveyor and reciprocable horizontally across said conveyor toward and from said support, means for separating the leading one of said succession of panels from succeeding panels therein, a stop engageable by said leading panel to stop the same in a position opposite the operative side of said pusher, means preventing retrograde movement of said leading panel after engaging said stop, power actuated means arranged to reciprocate said pusher to transfer said leading panel from said conveyor to said support, and means actuated in response to the accumulation of a predetermined number of said panels on said support to move said support to release said predetermined number of panels.

9. Apparatus for stacking wallboard panels and the like in a plurality of columns, comprising a horizontal conveyor adapted to convey a succession of said panels, a horizontal support arranged adjacent said conveyor and adapted to receive successively a plurality of said panels from said conveyor, a pusher arranged adjacent one side of said conveyor and reciprocable horizontally across said conveyor toward and from said support, means accelerating the leading one of said succession of panels to separate it from succeeding panels therein, means stopping the forward movement of said leading panel on said conveyor opposite the operative side of said pusher, power actuated means arranged to reciprocate said pusher to transfer said leading panel from said conveyor to said support, and means actuated in response to the accumulation of a predetermined number of said panels on said support to move said support to release said predetermined number of panels.

10. Apparatus for stacking wallboard panels and the like in a plurality of columns, comprising a horizontal conveyor adapted to convey a succession of said panels, guide means adjacent one side of said conveyor and guiding said panels in their movement along said conveyor, a horizontal support arranged adjacent said conveyor and adapted to receive a plurality of said panels in side by side relation from said conveyor, a pusher arranged adjacent one side of said conveyor and reciprocable horizontally across said conveyor toward and from said support, means for separating the leading one of said succession of panels from succeeding panels therein, means stopping the forward movement of said leading panel on said conveyor opposite the operative side of said pusher and in line with said support, power actuated means arranged to reciprocate said pusher to successively transfer said panels from said conveyor to said support, and means actuated in response to the accumulation of a predetermined number of said panels on said support to move said support to release said predetermined number of panels.

11. Apparatus for stacking wallboard panels and the like in a plurality of columns, comprising a horizontal conveyor adapted to convey a succession of said panels, guide means associated with said conveyor for guiding said panels in their movement along said conveyor and including a stationary guide plate adjacent one side of said conveyor, a pair of spaced horizontal retractable rails arranged adjacent said conveyor and adapted to receive a plurality of said panels in side by side relation from said conveyor and to engage said panels along their marginal portions, a push plate arranged adjacent one side of said conveyor in alignment with said guide plate and reciprocable toward and from said rails, means accelerating the leading one of said succession of panels to separate it from succeeding panels therein, a stop plate adjacent one of said rails and engageable by said leading panel to stop the same in a position opposite the operative side of said push plate, means preventing retrograde movement of said leading panel after engaging said stop, means reciprocating said push plate to transfer said leading panel from said conveyor to said rails, and means for retracting said rails to release the panels supported thereby when a plurality of said panels have accumulated thereon.

12. Apparatus for stacking wallboard panels and the like in a plurality of columns, comprising

a horizontal conveyor adapted to convey a succession of said panels, guide means associated with said conveyor for guiding said panels in their movement along said conveyor and including a stationary guide plate adjacent one side of said conveyor, a pair of spaced horizontal retractable rails arranged adjacent said conveyor and adapted to receive a plurality of said panels in side by side relation from said conveyor and to engage said panels along their marginal portions, a push plate arranged adjacent one side of said conveyor in alignment with said guide plate and reciprocable toward and from said rails, means accelerating the leading one of said succession of panels to separate it from succeeding panels therein, a stop plate adjacent one of said rails and engageable by said leading panel to stop the same in a position opposite the operative side of said push plate, means preventing retrograde movement of said leading panel after engaging said stop, means actuated in response to the engagement of said leading panel with said stop plate and reciprocating said push plate to transfer said leading panel from said conveyor to said rails, and means actuated in response to the accumulation of a predetermined number of said panels on said rails and retracting said rails to release said predetermined number of panels and permit them to fall by gravity.

13. Apparatus for stacking wallboard panels and the like in a plurality of columns, comprising a horizontal conveyor adapted to convey a succession of said panels, guide means associated with said conveyor for guiding said panels in their movement along said conveyor and including a stationary guide plate adjacent one side of said conveyor, a pair of spaced horizontal retractable rails arranged adjacent said conveyor and adapted to receive a plurality of said panels

in side by side relation from said conveyor and to engage said panels along their marginal portions, a push plate arranged adjacent one side of said conveyor in alignment with said guide plate and reciprocable toward and from said rails, means accelerating the leading one of said

succession of panels to separate it from succeeding panels therein, a stop plate adjacent one of said rails and engageable by said leading panel to stop the same in a position opposite the operative side of said push plate, means preventing retrograde movement of said leading panel after engaging said stop, means actuated in response to the engagement of said leading panel with said stop plate and reciprocating said push plate to transfer said leading panel from said conveyor to

said rails, and means actuated in response to the movement of said leading panel along said rails and retracting said rails to release a predetermined number of said panels accumulated on said rails and permit them to fall by gravity.

ALBERTA JEFFREY,

*Executrix of the Estate of Douglas C. Jeffrey,
Deceased.*
